C. W. RENNER

HEADLIGHT RAY DEFLECTOR

Filed June 9, 1920

INVENTOR
Charles W. Renner.

ATTORNEYS

UNITED STATES PATENT OFFICE.

CHARLES W. RENNER, OF ALTOONA, PENNSYLVANIA, ASSIGNOR OF ONE-HALF TO
JOSEPH J. NAGLE, OF PHILADELPHIA, PENNSYLVANIA.

HEADLIGHT RAY DEFLECTOR.

Application filed June 9, 1920. Serial No. 387,526.

To all whom it may concern:

Be it known that I, CHARLES W. RENNER, a citizen of the United States, residing at Altoona, in the county of Blair, State of Pennsylvania, have invented a new and useful Headlight Ray Deflector, of which the following is a specification.

My invention relates to a novel construction of a headlight ray-deflector, lamp mask, 10 light-ray diffuser shade, glare shade, or headlight-beam modifier, adapted to be applied to vehicle-lamps or headlights, to searchlights, high-powered lanterns and other forms of light reflecting devices, for 15 the purpose of dimming the glare-reflection of their lights.

My invention is especially adapted to the headlights of automobiles, in which it is desirable to intercept the upward and to some extent the forward rays of the light, and deflect it to the roadway to overcome the blinding glare, which as vehicles approach each other or approach an individual upon a roadway, tend to bewilder both the driver of the vehicle or the person coming into the path of the light.

To the above ends, my invention has for its principal object the construction of an inexpensive and effective deflector embodying an annular frame, from the upper portion of which projects a series of arcuate louvers of different lengths, which will possess the advantages of other more complicated and expensive structures, and, in addition, permit the employment of an ordinary plain lens or pane of glass, in lieu of the expensive, special lenses now generally employed to comply with special State legislation relating thereto.

For the purpose of illustrating my invention, I have shown in the accompanying drawings one form thereof which is at present preferred by me, since the same will give in practice satisfactory and reliable results, although it is to be understood that the various instrumentalities of which my invention consists can be variously arranged and organized.

Figure 1 represents a front elevation of a 20 headlight ray deflector embodying my invention.

Figure 2 represents a vertical section on line 2—2 of Figure 1.

Figure 3 represents a perspective view of

the front of an automobile having its headlights equipped with my invention.

Figure 4 represents on a reduced scale a side elevation of my deflector applied to a headlight.

Similar numerals of reference indicate corresponding parts.

Referring to the drawings:

1 designates a typical headlight or other lamp, which may be of any desired construction embodying an outer casing or body 45 and a suitable internal reflector, two of these headlights being shown in Figure 3 as mounted upon the front of an automobile 2, in any conventional manner.

My novel deflector consists of a preferably 70 circular frame 3, of metal or other material, and preferably also formed with a vertical or radially and outwardly extending rear flange 4, the dimensions and outlines of which enable it to be readily applied or secured to the body of the headlight proper by any preferred means, such, for instance, as the bolts 5 or the like seen in Figure 4.

The frame or ring 4 may be fitted or secured to the headlight or body by any other 70 fastening means, and serves as a carrier for a plurality of graduated, inclined, separated, crescent-shaped shades or reflectors, which in the art to which my invention appertains are usually denominated arcuated 85 louvers.

I preferably employ four of these louvers designated from the uppermost to the lowermost, as 6, 7, 8, and 9. The light reflecting surface of each louver decreases from the top louver to the bottom one, that is, the uppermost louver 6 has a forwardly and downwardly inclined extension, whose light reflecting area is greater than the next louver 7, while the corresponding surface of 90 the louver 7 is greater than the corresponding surface of the louver 8, which latter has a greater reflecting area than the bottom louver 9. Otherwise to express it, the forwardly extending, central, light reflecting area of each louver decreases downwardly, so that, considered together, they constitute a series of overhanging reflectors whose light reflecting surface increases from bottom to top, the effect of which is to cause the downward deflection of the light emanating from about the upper half of the

lamp and cause it to be thrown upon the

road, rather than directly forward in a horizontal plane.

- It will be apparent that in my device, plain glass discs may be employed in the headlights, and that, if desired, no glass discs may be employed, but it is of course preferable to use an outer glass disc to prevent dirt, dust and moisture from settling on the usual reflectors or their electric lights.
- 10 It will consequently be seen that in my device in the case of the breakage of either one or both glass discs, an automobilist can proceed at night to his destination, as my device will function effectively even if 15 both glass discs should accidentally become broken, since the provision of the louvers having their light deflecting and reflecting areas, arcuate and deflected downwardly and decreasing from the top downwardly, as 20 described, will effect the desired results under all conditions.

Inasmuch as the series of louvers which I employ is extended downwardly only to about the middle of the frame or ring 4, 25 it will be apparent that the louvers will affect or deflect only such portion of the light as in the illustration is thrown forward through about the upper half of the headlight, which permits the light rays emanating from the lower half of the headlight or lamp below its diametric horizontal center to be projected forwardly in a proper manner, the general collocation of said louvers being understood from Figure 2.

I do not, of course, confine myself to any special dimension for the light deflecting areas of the louvers as a group, but said area in each louver decreases downwardly, 40 or gradually diminishes in extent, outline and area, so that the lowermost louver 9 is about half the size of the uppermost louver 6, while the two intermediate louvers are graduated as to their light reflecting or 45 deflecting area between the dimensions of the uppermost and the lowermost of the group, so that said area of each louver decreases from the top one downwardly, and it will be apparent that the proportioning or collocation of the louvers may be 50 varied according to requirements, both as to the number of louvers employed, the distance they are spaced apart, and the extent of their light reflecting and deflecting area, 55 it being, however, essential that said area of each louver decreases downwardly.

The method of connecting the louvers to their frame 4 may obviously be varied. In

practice, the terminals 10 of the louvers may be deflected against the juxtaposed portion of the frame 3 and secured thereto by spot-welding, riveting or any other desired means.

The frame 3 may be secured to the body 1 by any suitable means, as the fastening devices 5, and it will be obvious that when the parts are assembled as seen in Figure 3, the light will be properly reflected and deflected to the desired points and to the desired extent, and by reason of the inclination of the louvers, the deflected rays may be caused when the device is used upon an automobile, to strike the ground at such distance in advance of the latter as may be desired.

It will now be apparent that I have devised a novel and useful headlight ray deflector which embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent, is:—

In a head light ray deflector, an annular frame, and a plurality of crescent shaped forwardly and downwardly inclined louvers located in the upper portion only of said frame, and projecting forwardly therefrom and having their outer terminals attached to the curved side walls of said frame, the reflecting area of each louver decreasing downwardly from the upper to the lowest louver, the rear curved edge of the upper louver being secured to the upper inner periphery of said frame, and the lower louver having its outer ends secured to said frame on about the horizontal median line of said frame, the space between each of said louvers and below the lower louver being entirely open and unobstructed, and the forward upper edge of each louver being behind the upper edge of the louver immediately above it.

CHARLES W. RENNER.
